[57] CLAIM

The ornamental design for a lined box, as shown and described.

DESCRIPTION

FIG. 1 is a front perspective view of the invention in collapsed form;

FIG. 2 is a rear perspective view of the invention in collapsed form, the lining is shown in an alternate position for clarity of illustration; and,

FIG. 3 is a front perspective view of the invention in assembled form, the rear perspective view being identical. The broken line showing of the lid in FIG. 3 is for illustrative purposes only and forms no part of the claimed design.
